UNITED STATES PATENT OFFICE.

KEISHIRO KUNISHIGE, OF LOS ANGELES, CALIFORNIA.

TAKEDOWN TABLE.

1,397,764.

Specification of Letters Patent. Patented Nov. 22, 1921.

Application filed November 23, 1920. Serial No. 425,939.

To all whom it may concern:

Be it known that I, KEISHIRO KUNISHIGE, a subject of the Emperor of Japan, residing in the city and county of Los Angeles and 5 State of California, have invented a new and useful Takedown Table, of which the following is a specification.

This invention relates to improvements in tables, and has for its objects the 10 vision of improved means for taking down and reassembling tables in an expeditious manner, and to provide a table of simple design, which, in the take-down position, can be packed in small space for storage or 15 shipment.

The invention further includes an improved construction of table top whereby the same may be made more ornamental in appearance, and better provision is made 20 against warping or displacement of the material composing the table-top.

Other objects and advantages will become apparent from the following description and subjoining claims.

Upon the drawings, Figure 1 is a top plan view of a table embodying my invention. Fig. 2 is a perspective view of the same. Fig. 3 is a vertical and sectional view of the table; a pair of the legs being shown in 30 full. Fig. 4 is a perspective view of a pair of the table legs. Fig. 5 is a plan view of the lower center plate. Fig. 6 is a top plan view of a modified form of table top construction. Fig. 7 is a transverse and 35 sectional view of a modified form. Fig. 8 is a fragmentary and bottom plan view of the table top. Fig. 9 is a top plan view of the base, as shown in Fig. 7. Fig. 10 is an end view of the central supporting member. Fig. 11 is a side view of the central supporting member.

Referring to the drawings, I have provided a circular table-top 21, which is constructed of segmental pieces 22, in this case, 45 glued together to form the top, and reinforced by the under-plate 23, an annular depending flange 24, and cross-bars 25, which are provided with elongated holes 26. The particular construction of the top affords a means for producing an ornamental 50 effect, as alternate segmental parts may be made from a dark wood and light wood, and also affords a non-warpable top. The detachable legs 27, are provided with mortise- 55 ends 28, adapted to engage with holes 26, and are connected in pairs by upper braces

29 and 30, and by lower braces 31 and 32. A bolt 33, passing through upper braces 29 and 30, screws into the cross-bars 25, and similarly, a bolt 34, passing through lower 60 braces 31 and 32, screws into the center-plate 35. The leg-braces 29 and 31, are provided with mortise-notches 36, and leg- 65 braces 30 and 32, with corresponding notches, so that, when assembled, a rigid structure is produced, and the legs are held in alinement with one another and with the top.

To take down the table, the bolts are first removed. The top and center-plate 70 are then detached, and the legs are then collapsed by folding one pair upon the other.

In the modified form of top shown in Fig. 6, I provide a small circular center piece 37, 75 and the alternating segmental pieces 38 and 39, have their inner ends abutting against and glued to the center piece.

In the table shown in Figs. 7, 8, 9, 10 and 11, I provide a central supporting member 80 40, having a notched end 41, adapted to engage with the top cross-bars 25, and a notched end 42, adapted to engage with the base 43. A bolt 44, passing through the base, screws into the cross-bars 25. It is 85 to be understood that each table as constructed, is provided with a top, and with detachable legs and center plate as shown in Figs. 2, 3, 4 and 5, and with detachable base and central supporting member as 90 shown in Figs. 7, 9, 10 and 11.

What is claimed is:

1. In a take-down table, the combination with a top having an integral depending flange on the underside, of angular brace-bars disposed on the underside of the top and extending radially from the center to the depending flange, the said brace-bars being fixed to the top and having elongated openings on the bottom, detachable legs, 95 mortise ends on the legs engaging with said elongated openings, braces connecting the legs in pairs, a center plate, and bolts passing through the leg braces and screwing into the top brace-bars and into the center-plate.

2. In a take-down table, the combination with a top having radial brace-bars fixed to the underside, of detachable legs, braces connecting the legs in pairs and having corresponding mortise notches, mortise ends on the legs adapted to engage with corre- 110

sponding slots in the top radial brace-bars, said pairs of legs being interlocked, a center-plate disposed beneath the top, and bolts passing through the leg-braces and screwing 5 into the radial bars and into the center-plate.

3. In a take-down table, the combination with a top having radial slotted brace-bars on the underside, of detachable legs engag- 10 ing with the slots in the radial bars, upper

and lower braces connecting the legs in pairs, and having mortise notches for maintaining the braces in angular position relative to one another, a center-plate disposed on the bottom braces, and bolts passing 15 through the leg-braces and in screw engagement with the top and center-plate.

In testimony whereof, I hereunto affix my signature, this 13th day of Nov., 1920.

KEISHIRO KUNISHIGE.
